MINE CAR

Otto Sann, Johnstown, Pa.

Application December 5, 1931, Serial No. 579,282

2 Claims. (Cl. 105—364)

This invention relates to mine cars and particularly to improvements in axle construction thereof. The invention aims particularly to provide an improved form of axle which forms a support for the bottom and parts of the side of the car, the axle structure including a detachably mounted stub axle, the fastening means of which are accessible from the interior of the car so that when the stub axle becomes bent, badly worn or otherwise damaged, it can be readily removed for replacement or repair without disturbing or dismantling other parts of the car or its underframe.

10 The invention will be fully apparent from the following specification when read in connection with the accompanying drawings.

In the drawings:—

Fig. 1 is a plan view of a mine car embodying my invention, many of the detailed features usually found in mine parts being omitted in the interest of clearness;

Fig. 2 is a side elevation of Fig. 1 with parts broken away;

Fig. 3 is a transverse section on line 3—3 of Fig. 2, showing the improved axle and its relationship to other structural parts of the car;

Fig. 4 is an enlarged detail illustrating the preferred mounting for the detachable axle spindle.

30 Referring in detail to the drawings, the mine car includes any suitable form of underframing and a central strengthening member such as indicated generally at 10. These parts may follow the usual and standard design. The car will include the usual bottom plates 12 and side plates 14. The characteristic feature of my improved construction resides in the design and arrangement of the axle portions. These axles are indicated as a whole at 16—16 in the drawings.

40 The two axles are of substantially identical construction and a description of one will suffice for both. As best shown in Fig. 3, the axle consists of a substantially U-shaped member, the drop-center portion 18 of which serves to support the floor plates 12. It is also secured to the central longitudinally extending member 10. At each side, the axle has upstanding legs 20. These serve as supports for wheel hoods 22 which in effect constitute part of the car bottom. These 50 hoods are flanged as at 24 and are riveted or otherwise secured to the side plates 14 of the car body.

In the fillet-zone of the axle, where the leg 20 merges with and joins the drop central portion 55 of the axle, I provide an enlarged spindle pocket

boss 26. This hub, as indicated in plan, in Figs. 3 and 4, projects into the interior of the car. This is important, as it provides easy access to the axle spindle 28, which is removably secured to said boss by means of a key 30, which passes transversely through the boss and the spindle. The end of the boss 26 is provided with an aperture 32 which is aligned axially with the axis of the spindle 28. This spindle, as shown, forms a support for suitable roller bearings 34 mounted within 65 suitably formed sockets in the car wheel 36. The wheel is held on the spindle by means of a nut 38 secured to a suitable threaded shank formed on the extremity of the spindle, this nut being locked by a cotter pin in a known manner.

70 In the arrangement above described, it will be appreciated that the mine car wheel is located below the hood 22 and each axle as a whole is riveted or otherwise permanently incorporated in the underframe and bottom structure of the car. 75 With the improved construction described, it is clear that in the event that the spindle 28 becomes badly worn, bent, or damaged, it can be readily removed from the car without materially dismantling any part of the underframe structure. 80 And such removal can be readily accomplished by relatively unskilled workmen.

To remove the spindle, it merely necessitates either jacking up or blocking up the drop central portion of the axle and removing the key 30, 85 whereupon a drift pin can be inserted in the aperture 32 and the spindle driven out of the boss 26 by a sledge hammer. And such removal can be effected without even dismantling the wheel until after the parts have been dismounted. It is 90 noted that the operation of removing the spindle can be effected from the interior of the car. This greatly facilitates the work and constitutes an important feature of the invention.

95 While I have described quite precisely the details of the embodiment of the invention illustrated, it is to be understood that various modifications may be made by those skilled in the art without departing from the invention as defined in the appended claims.

100 What I claim is:—

1. A mine car, an axle extending transversely of the car having a dropped center portion with upstanding legs at each end thereof, spindle pocket bosses merging into each leg and said drop center portion, wheel supporting spindles removably seated in each of said bosses, keys securing said spindles to said pocket bosses, the axis of each spindle lying in a plane spaced above the top of said drop center portion and each boss 110

being apertured for the insertion of a tool by means of which the spindle can be driven from its supporting boss and wheel hoods secured to said upstanding legs.

5 2. A mine car including supporting axles formed with central drop portions with upstanding legs at the ends thereof, a longitudinally extending frame member secured to said axle, a bottom floor plate secured to said axle, wheel hoods secured

to said upstanding legs, side plates secured to said wheel hoods, spindle pocket bosses formed on said axle at the point of juncture between the drop center portion and said legs, removably mounted wheel supporting spindles carried by 80 said pocket bosses, means located in a plane above said floor plates for detachably securing said spindles to said bosses.
